Attorney,

UNITED STATES PATENT OFFICE.

MELLEN N. BRAY, OF BOSTON, MASSACHUSETTS.

SCREW-PROPELLER.

SPECIFICATION forming part of Letters Patent No. 554,331, dated February 11, 1896.

Application filed June 27, 1895. Serial No. 554,264. (No model.)

To all whom it may concern:

Be it known that I, MELLEN N. BRAY, of Boston, in the county of Suffolk and State of Massachusetts, have invented certain new and useful Improvements in Screw-Propellers, of which the following, taken in connection with the accompanying drawings, is a specification.

My invention relates to screw-propellers, and has for its object so constructing the propeller that the angles of its blades may be reversed, in order to reverse the motion of the boat, without reversing the engine or changing the direction of the revolution of the propeller-shaft; and it consists in certain novel features of construction, arrangement, and combination of parts which will be best understood by reference to the description of the accompanying drawings and to the claims hereto appended, and in which my invention is clearly pointed out.

Figure 1 of the drawings is a plan of a screw-propeller, illustrating my invention. Fig. 2 is a side elevation of the same with a portion of the propeller-hub cut in section on line 1 1 on Figs. 1 and 3. Fig. 3 is a sectional elevation, the cutting-plane being through propeller-shaft on line 2 2 on Fig. 2. Fig. 4 is a section on line 3 3 on Fig. 2. Fig. 5 is an elevation of one of the propeller-blades detached from its hub. Fig. 6 is an end view of said blade. Fig. 7 is a plan of the propeller-hub with the blades and the journal-caps removed. Fig. 8 is an elevation of the outer end face of the same. Fig. 9 is a section on line 4 4 on Fig. 8. Figs. 10, 11, and 12 are respectively a plan, a rear elevation, and an end view of the cap of the journal-box. Fig. 13 is a side elevation of the reversing-hub and portions of the crank-engaging bars. Fig. 14 is a transverse section on line 5 5 on Fig. 13, looking toward the left of said figure. Figs. 15 and 16 are respectively a side elevation and an end elevation of the shipper-yoke, and Figs. 17 and 18 are respectively an elevation and an edge view of the crank-pin block.

In the drawings, A is the propeller-shaft having a portion of its length near its rear end made tapering to receive the hub B, having a correspondingly-tapered central bore, and secured upon said shaft by the clamping-nut *a* and the check-nut *a'* fitted to the threaded end portion of said shaft, as shown in Fig. 4.

The hub B has formed integral therewith the two laterally-projecting half-boxes B', to which are bolted the caps B² to form two journal-boxes in which are mounted the journals C' of the propeller-blades C, as shown in Figs. 1 and 2. Each of the journals C' of the blades C has formed upon its inner end a crank *b* provided with a crank-pin *b'*, upon which is fitted the rectangular block *c*, said cranks being inclosed in the chambers *d d* formed in the hub B and movable about the axes of said journals C a distance equal to about forty degrees, more or less, to vary the pitch of the blades C or to reverse their angular positions relative to a plane cutting through their axes at right angles to the axis of the propeller-shaft.

The inner end of the hub B has formed therein a cylindrical chamber B³ to receive the reversing-hub D, which is fitted upon the shaft A so as to be movable endwise thereof and revoluble therewith and has secured thereto the two rearwardly-projecting arms D' D', which are fitted to suitable bearings in the hub B and are provided near their rear ends with rectangular notches to engage the blocks *c c* mounted on said crank-pins *b'*, as shown in Fig. 2.

The reversing-hub D has formed thereon the annular groove *d'*, to which is fitted the shipper-yoke E, provided with the two opposite trunnions *e*, which are to be engaged by any suitable shipper lever or rod (not shown) arranged to move said yoke and hub to and fro parallel with the axis of the shaft without interfering with the revolution of the said shaft and the propeller.

The operation of my invention is as follows: The blades of the propeller being set as shown in the drawings, the shaft A is revolved in the direction indicated by the arrow on Fig. 3, when the boat will be driven ahead. If it is desired to check the speed of the boat and move it astern suddenly the engineer moves the yoke E and the hub D toward the rear, when the angles of the blades C will be reversed, and without stopping or reversing the rotation of the shaft A the motion of the boat will be reversed. This is a great advantage, particularly in small boats the engines of which are not provided with reversing-gears. As the hub D fits the

cylindrical chamber B^3 closely the wall of said chamber is provided with vent-holes $f f$ for the escape of water from said chamber when said hub is moved into the same.

5 What I claim as new, and desire to secure by Letters Patent of the United States, is—

1. In a screw-propeller, the combination of an operating-shaft: a hub secured to said shaft in a fixed position and provided with a plurality of journal-boxes to receive the journals of the propeller-blades, and with a plurality of longitudinal guideways arranged eccentric to the axis of revolution of said hub: a plurality of blades revolvably mounted 10 in said journal-boxes: a crank formed upon, or secured to, the inner end of each of the journals of said blades: a hub fitted upon, revolvable with, and movable endwise of said operating-shaft, and provided with a circumferential groove: a plurality of bars fitted to said longitudinal guideways so as to be supported thereby, and movable endwise therein, and firmly secured at one end to said endwise-movable hub, and provided, at their other 15 ends, with rectangular transverse notches or

grooves: a rectangular block mounted upon each crank-pin of said blades, and engaged by said rectangular notches in said bars: and means for moving said hub and bars endwise of the propeller-shaft.

2. The combination of the shaft A; the hub B provided with the boxes B' B^2 and with longitudinal guideways eccentric to its axis of revolution; the blades C provided with the journals C' ; the cranks b ; crank-pins b' ; the blocks c fitted to said crank-pins; the hub D provided with the circumferential groove d' ; the shipping-yoke E; and the arms D' fitted to and supported by said guideways, and connecting said hub D to the cranks b all constructed and operating substantially as described. 30

In testimony whereof I have signed my name to this specification, in the presence of two subscribing witnesses, on this 24th day 35 of June, A. D. 1895.

MELLEN N. BRAY.
